UNITED STATES PATENT OFFICE

2,661,080

CONVEYER TABLE

James Xenakis, Long Branch, N. J.

Application August 4, 1949, Serial No. 108,463

2 Claims. (Cl. 186—1)

1

This invention relates to conveyor-tables which may be used for a number of purposes.

An object is to provide a conveyor-table adapted to receive articles placed thereon from a plurality of loading stations located adjacent one or both sides of the conveyor.

Another object is to provide a conveyor-table having means associated therewith for moving and cleaning the conveyor belt, said cleaning means being operative while the conveyor is in operation.

Another object is to provide a conveyor-table having a shelf or shelves above the conveyor and a liquid supply pipe extending longitudinally of the conveyor to deliver liquid to users located adjacent the conveyor or to deliver liquid to objects carried thereby.

A further object is to provide a unit comprising the table and conveyor with its associated parts, as hereinafter described, which can be easily installed with a minimum of labor and material.

Other objects and advantages will be apparent from the following specification and annexed drawings wherein:

Figure 1 is a perspective view of a conveyor-table embodying the invention;

Figure 2 is a longitudinal sectional view of the table shown in Figure 1; and

Figure 3 is a transverse sectional view of the table on the line 3, 3—Figure 1.

For the sake of illustration, the invention is shown as applied to a table for restaurant use, but it will be understood that it may be used for other purposes, as for example, on an assembly line, as hereinafter briefly referred to.

In restaurants, usually of the cafeteria type, the customer upon entering the restaurant picks up a tray, water glass, cutlery, etc., and then proceeds to a selection of food usually displayed on long counters or vended from slot machines.

Having selected the food and placed it on the tray, the customer then proceeds to locate a table, places the tray thereon and consumes the food. When finished, the customer usually leaves the tray, dishes, etc., for an attendant to recover for washing.

This procedure often results in the dirty dishes remaining on the tables for some time, thus preventing the use of the table, and being otherwise objectionable for obvious reasons. An object of the present invention is to eliminate this objection and provide for the immediate removal of the trays and dishes as soon as the customers have finished with them.

A typical installation consists of a horizontal 55 conveyor belt

2

belt conveyor wide enough to accommodate restaurant trays as explained hereinafter. A series of stationary rails constituting receiving points are arranged alongside the conveyor and on both sides of it, unless one side of the conveyor is against a wall of the building.

These racks, or rails, are designed to receive the loaded tray as brought by the customer. In front of each pair of racks is a stool or a chair where the customer is seated. Once the tray is placed upon one of the racks, it forms a perfect table and thus the customer proceeds to eat without the necessity of transferring any of the dishes to another table. At least a portion of the bottom of each tray is exposed between each set of rails which makes it easy to remove the trays. As soon as the customer is ready to leave, he simply pushes the tray with its contents onto the conveyor by pushing upwardly on the bottom of the tray and sliding it inwardly to the conveyor which carries the tray to the unloading point or into a washer. Other pieces of dinnerware may be placed on the conveyor from time to time if necessary during the repast and the tray disposed of last of all.

In this manner the eating space is perfectly cleared for the next customer, eliminating in this manner the difficult process of cleaning tables, collecting trays scattered about in the dining room etc. Should a customer omit to push his own tray into the conveyor, the next customer does so by pushing it with his loaded tray.

Under the racks and under the conveyor in front of the customers' knees are provided adequate shelves or racks, whereupon the customer may place his hat, bag, case, coat, etc. These shelves are properly partitioned to avoid mistakes when recovering these articles.

Small shelves are disposed along the conveyor, on stationary brackets every six or so feet, carrying such necessities as salt, pepper, chilli, etc., or one shelf may extend the entire length of the conveyor.

The conveyor always presents a clean surface as it moves in front of the customers, and the conveyor may be continually washed at the receiving end, if necessary, either automatically by a rotating brush as herein described, or manually. Thus, any spilling of food on the conveyor will be washed off as soon as it begins its return travel from the delivery end.

In conjunction with the above, it is possible to eliminate the use of separate dishes by imparting three or four unlike forms on the tray itself, either by stamping, moulding, etc. When select-

ing the food items at the counter the tray is pushed by the customer under the glass case towards the counterman, whereupon the counter, or service man pours the food directly into the tray without having to handle any dishes. In such a case the glass cases between the customer and the food counter must be raised a few inches in order to allow the passage of the tray towards the food counter and back to the customer. Such trays, having symmetrical dish stampings at their bottom (say three or four dishes) afford no difficulty in stacking and present perfect stability when resting on, or being pushed along a flat surface. As such compartment trays are already known, they are not here described in detail.

The necessary apparatus for an installation as just described has a framework composed of vertical side members 10, 11 and horizontal wall members 12, 13, and ends 14, 15. Bearings 16 of any suitable type support the rollers 17 supporting the endless conveyor belt 18, 18a of any suitable construction. This may be a canvas-rubber belt having a white flexible plastic facing so as to present a clean, pleasing appearance.

The belt as shown in Figure 1 extends downwardly at the delivery end into a cleaning tank 19 where it is engaged and driven by a feed roller 20 suitably supported in the tank and driven in any suitable manner by a motor 21 supported outside the tank on a side wall thereof or in any suitable manner.

Suitably supported on the side walls of tank 19 are the cleaning brushes 22, 23 of any suitable construction. These may be driven by motor 21 and are located below the liquid level 24. Wipers 25, 26 wipe the surplus liquid off the belt as it emerges from the liquid.

The lower run 18a of the belt extends longitudinally through the drying chamber 25 formed between the lower run 18a of the belt and the horizontal wall member 12.

A suitable blower 26 having a motor 27 (or it may be driven by motor 21) discharges air at 28 (which has been heated by any means such as steam coils 29) into the chamber 25 from which the air is withdrawn by duct 30.

Duct 30 opens into a chamber 31 formed by walls 12, 13, 32, 33 and from 31 returns to the blower.

The hot air in chamber 25 impinges on the lower face of the lower run 18a of the belt which, in consequence thereof, is dried before it becomes the upper surface of the upper run 18 of the belt.

The loading stations may be located on one or both sides of the conveyor-table. As all of them are the same in construction, only one of them will be described.

Each station comprises a pair of rails or racks 34, 35, secured to the main framework and extending outwardly therefrom to form spaced-apart supports for a tray 36 which freely slides between the rails. The inner edge of the tray may abut the longitudinally extending members 37 of the framework which is bent upwardly as indicated at 38 so that a slight inward push is necessary to cause the tray to ride over the hump 38 and slide onto the conveyor 18.

The inner edge of the member 37 overlies the edge of the belt 18 as shown at 39, and the conveyor belt at this point may have an upstanding lip or bead to extend upwardly into and below the edge 39 to insure that anything spilled at this point will not run off the sides of the conveyor.

The rails are preferably made in adjacent

pairs. Such a pair is shown at 35, 40, Figure 1. Upstanding ribs 41, hold adjacent trays such as 36, spaced apart. A web 42 is between adjacent stations sufficiently wide to provide elbow room for adjacent users of the stations, such as those who would be seated on stools 43, 44.

It will be observed that the space between rails at each station, for example between rails 34 and 35, is free and open so that the bottoms of the trays, such as 36, are open to permit the person handling them to easily place them in position while supported on one hand below the tray. This also aids the user when pushing the tray from the rails to the conveyor.

10 The legs 45 spaced at suitable intervals support the outer ends of the rail members and also support the entire unit structure as best seen in Figure 1.

15 A plurality of shelves 46 supported on standards 47 or in any other suitable manner are located along the conveyor. Instead of a plurality of shelves, one long shelf may extend the entire length of the unit. As such a modification is obvious from what is here shown, it is not 20 herein described.

25 A liquid supply pipe 48 may be supported under the shelves 46 and provided at suitable intervals with valves 49 so that in the case of restaurant tables the customers may obtain water without 30 leaving their seats.

The walls 10, 12, 13, 33, 32 together with transverse walls 50 form a plurality of individual compartments in the unit structure, one for each station. Access to these compartments is obtained via openings 51 located immediately in 35 front of each station and easily accessible to the user who can store therein his hat and other impedimenta while using the table.

40 If desired the conveyor-table just described and the stools may be mounted on a platform 52 so that it may be placed in working position and moved from time to time as a unit.

45 The operation of the device will be apparent from the foregoing. At the delivery end of the conveyor there is a receiving counter having a hinged top 53 which may lie flat as shown in Figure 2 so that trays will be slid thereon, one after the other, by the action of the conveyor belt. The table top 53 may be located in another room from the conveyor, and an attendant may remove the trays and dishes from the fixed rear portion 54 of the counter.

50 If desired, the hinged top 53 may be elevated as shown at 55 whereupon the trays and their 55 contents will remain on the conveyor and be carried downwardly into tank 19 until they encounter the downwardly sloping ramp 56 which gradually conveys them into the detergent liquid in the tank, or conveys them into another tank or dishwasher.

56 In some instances it is desirable to make the conveyor belt of stainless steel. Such a thin stainless steel belt may be imperforate, or it may be perforated along its edges to be driven by sprockets similar to a motion picture film. As such a construction of the belt is obvious from the foregoing description it is not here shown in detail. When the unit includes a stainless steel belt, it is at once apparent that it may be very 60 efficiently cleaned and fumigated and that such construction eliminates difficulties heretofore met with in apparatus of this character where, unless completely disassembled, it is impossible to clean out roaches and other insects which get into the

crevices throughout the device. With the present invention, it is possible to place a suitable germicidal or fumigating agent in the blower 26 and, by covering the entire unit with a tarpaulin, any suitable gas may be distributed throughout the unit penetrating every crack and crevice therein and completely sterilizing all parts of the device.

While the unit table-conveyor has been described in connection with restaurant use, it may be employed to advantage in a large number of other applications. For example, in connection with assembling light articles to be sprayed, the assemblers sit on the stools and each is provided with a tray containing the parts of the device to be assembled. The device is assembled on the tray and when the parts are assembled, the tray with the assembled article is pushed onto the conveyor. The completed article on the tray may be sprayed with lacquer or a protective coating via the pipe 48 which may then be equipped with any suitable form of spray nozzles instead of the faucets 49. The sprayed articles are conveyed to the table 54 in the manner previously described. If desired, an attendant provided at the table 51 at the starting end of the conveyor (and said table may be mounted upon the base 52) may supply parts to the assemblers seated on the stools by moving the parts from the table 51 on to the conveyor belt so that a great deal of running around on the part of the assemblers is eliminated.

The constructional details of the unit have not been gone into in detail as it is obvious that the framework of the unit may be quickly assembled by welding. The rails 34, 35 may also be welded to the main assembly, and the legs 45 can be welded to the rails and the side walls, such as 10 and 11.

As the fabrication of structures of this character is well understood, it is believed that other details of construction will be obvious to those skilled in the art.

What is claimed is:

1. A restaurant table structure comprising a horizontal frame open along its top and having longitudinally extending side walls, an endless conveyor belt extending longitudinally in said frame between the side walls thereof and having an upper flight exposed through the open top of the frame, tray supports disposed laterally of said frame and projecting outwardly from the side walls thereof forming service stations, shelves supported between said service stations and ex-

tending over said conveyor, strips extending along upper edges of said side walls and having portions projecting outwardly from the side walls at a downward incline in overlying relation to inner portions of the trays and also having portions projecting inwardly from the side walls at a downward incline and overlapping side edge portions of the upper flight of said conveyor belt, portions of said conveyor extending downwardly at one end thereof, and a rotary brush mounted in said frame to contact said downwardly extending portion of said belt.

2. A restaurant table structure comprising a horizontal frame open along its top and having longitudinally extending side walls, an endless conveyor belt extending longitudinally in said frame between the side walls thereof and having an upper flight exposed through the open top of the frame, tray supports consisting of brackets spaced from each other longitudinally of the side walls and projecting outwardly therefrom and providing service stations carrying tray supporting plates carried by said brackets and disposed laterally of the walls in position for engaging under side edge portions of trays and provided with upstanding longitudinally extending ribs for engaging side edges of trays resting upon the plates, shelves supported between said service stations and extending over said conveyor, strips mounted along upper edges of said side walls and having side portions overlapping inner ends of said plates and other side portions overlapping side portions of the upper flight of said conveyor, portions of said conveyor extending downwardly at one end thereof, and a rotary brush mounted in said frame to contact said downwardly extending portion of said belt.

JAMES XENAKIS.
